(57) **CLAIM**

I claim the ornamental design for a slip-on coupling assembly, as shown and described.

DESCRIPTION

FIG. 1 is a perspective view of a slip-on coupling assembly of the design described herein.

FIG. 2 is a left side view thereof.

FIG. 3 is a right side view thereof.

FIG. 4 is a front side view thereof.

FIG. 5 is a top side view thereof.

FIG. 6 is a bottom side view thereof; and,

FIG. 7 is a sectional view thereof taken along the line 7-7 as shown in FIG. 4.
